Primary Examiner — Paula Allen Greene(74) *Attorney, Agent, or Firm* — David W. Carstens;
Krista Y. Chan; Carstens & Cahoon, LLP(57) **CLAIM**

The ornamental design for a cremation urn, as shown and described.

DESCRIPTION

FIG. 1 is a perspective view of the cremation urn;
 FIG. 2 is a perspective view from the bottom of the cremation urn;
 FIG. 3 is a front view of the cremation urn;
 FIG. 4 is a back view of the cremation urn;
 FIG. 5 is a top view of the cremation urn;
 FIG. 6 is a bottom view of the cremation urn;
 FIG. 7 is a left side view of the cremation urn; and,
 FIG. 8 is a right side view of the cremation urn.
 The broken lines used to form the bottom of the cremation urn form no part of the claimed design. The broken lines depict environment that forms no part of the claimed design.
